United States Patent Office

Des. 181,827
Patented Dec. 31, 1957

181,827

BEACH CHAIR

James G. White, Chicago, Ill.

Application June 29, 1955, Serial No. 36,761

Term of patent 3½ years

(Cl. D15—8)

FIG. 1

FIG. 2

FIG. 3

Fig. 2 is a rear elevational view thereof;

Fig. 3 is an isometric view thereof; and

Fig. 4 is a side elevational view thereof.

I claim:

The ornamental design for a beach chair, as shown.
